(57) **CLAIM**

I claim the ornamental design for the balloon target apparatus, as shown and described.

DESCRIPTION

FIG. 1 is a front, top, and left perspective view of a first embodiment of the balloon target apparatus;

FIG. 2 is a front elevational view of the first embodiment of the balloon target apparatus;

FIG. 3 is a rear elevational view of the first embodiment of the balloon target apparatus;

FIG. 4 is a left side elevational view of the first embodiment of the balloon target apparatus;

FIG. 5 is a right side elevational view of the first embodiment of the balloon target apparatus;

FIG. 6 is a top elevational view of the first embodiment of the balloon target apparatus;

FIG. 7 is a bottom elevational view of the first embodiment of the balloon target apparatus;

FIG. 8 is a front, top, and left perspective view of the first embodiment of the balloon target apparatus inserted into a wall with the wall shown in broken lines;

FIG. 9 is a front, top, and left perspective view of a second embodiment of the balloon target apparatus;

FIG. 10 is a front elevational view of the second embodiment of the balloon target apparatus;

FIG. 11 is a rear elevational view of the second embodiment of the balloon target apparatus;

FIG. 12 is a left side elevational view of the second embodiment of the balloon target apparatus;

FIG. 13 is a right side elevational view of the second embodiment of the balloon target apparatus;

FIG. 14 is a top elevational view of the second embodiment of the balloon target apparatus; and,

FIG. 15 is a bottom elevational view of the second embodiment of the balloon target apparatus.

The wall in FIG. 8 is shown in broken lines for illustrative purposes only and forms no part of the claimed design.
